Application March 4, 1931, Serial No. 520,074

2 Claims. (Cl. 196—107)

Our invention relates to the treatment of hydrocarbon oils and especially to apparatus adapted to produce motor fuel from petroleum by the process commonly known as cracking. The present application is a continuation in part of each of our prior copending applications Serial No. 254,753, filed February 16, 1928; Serial No. 361,015, filed May 7, 1929, which has matured into Patent No. 1,821,116 and Serial No. 442,871, filed April 9, 1930. In these prior applications we have described and claimed an improved method of cracking under sub-atmospheric pressure, a complete plant for practicing the same, and an improved heater particularly adapted for use in our cracking still. In the present case we shall describe the same general system, comprising among other pieces of apparatus the following: a pre-heater operating preferably under pressure; a flashpot into which the heated oils are admitted and flashed into vapors; a cracking still receiving the vapors from the flashpot, and heating the same to a high temperature; a vapor pump or equivalent suction means withdrawing the vapors from the cracking still so as to maintain sub-atmospheric pressure therein and through the open connection of said still with said flashpot, also maintaining a sub-atmospheric pressure on said flashpot; means connecting the output side of said vapor pump or equivalent with fractionating apparatus, and therethrough with cooler and separator and/or other desirable or necessary pieces of apparatus. In our prior application Serial No. 361,015, we have claimed means for maintaining a constant vacuum or sub-atmospheric pressure on the cracking still and the flashpot in combination with means for refluxing and reheating condensed oils and passing the same back under pressure to the flashpot; also the same elements in combination with heat exchangers in the several fractionating units; also the same including a vacuum pump connected to produce a sub-atmospheric pressure on the entire system from the cooler back to the cracking heater. In the present case, we shall describe and claim that specific form of the invention in which the pump which creates the vacuum or sub-atmospheric pressure on the cracking coil has its outlet directly connected to the first dephlegmator or fractionator, whereby only the flashpot and cracking coil are under a sub-atmospheric pressure and the rest of the system operates above atmospheric pressure. In addition to this, we shall claim broadly herein the combination of primary heating means, a flashpot, cracking still, cooling and separating means, and means to create and maintain a sub-atmospheric pressure on the cracking coil.

Our apparatus, as it will be described herein, comprises a charging pump, for putting in the charging stock, a flashpot, a cracking still, a succession of interrelated fractionating towers or dephlegmators with necessary pumps, heat exchangers, cooler and separator, and finally means for feeding make-up oil into the system and back through heat exchangers to the flashpot, under pressure. This will be described in combination with refluxing heavy condensates, but the same will not be claimed herein, being claimed in combination with the other features in the parent application, Serial No. 361,015. In addition to the regulation of pressure in the flashpot and cracking still, we have found it possible to arrange a graduated heat transfer by means of which the make-up oil or reflux fractions to be cracked, take up practically all the heat energy in the cracked vapors, in a counter progression to the fractionator. The make-up oil and reflux fractions instead of going direct to the cracking still, have their temperature raised so that they can be converted into vapors in the flashpot; and by complementary regulation of the charging oil on the one hand and the make-up oil on the other, the quantity, the temperature, and the pressure of the hot oil admitted to the flashpot can be regulated to a nicety, with a minimum consumption of fuel in the primary heater since a large part of the heat ordinarily lost in the fractionating and cooling system is conserved in our system.

By maintaining a vacuum or a sub-atmospheric pressure in the cracking zone and flashpot, cracking commences at a lower temperature, while the raising of the temperature, together with the turbulent and rapid motion of the vapors through the cracking tubes due to the pull of the vacuum, causes a considerable increase in the amount of heat energy taken up per square foot of surface, with a corresponding increase in the amount of cracked products. Without limiting ourselves to one specific set of pressures, we have found in actual practice that suitable pressures for our system and our method are from 15 to 75 pounds absolute on the primary heating still, from 12 to 14 pounds absolute on the flashpot, and from 6 to 14 pounds absolute (or a higher vacuum) on our cracking zone. It is to be understood that the word "vacuum" as used in this specification means therefore any pressure below that of the atmosphere, but the actual pressures employed will be stated in pounds absolute.

Our invention is illustrated in the accompanying drawings, in which

Fig. 1 is a diagrammatic side elevation with parts in section showing the general arrangement of our apparatus.

Fig. 2 is a similar view of a modification showing a different form of preheater.

Fig. 3 is a similar diagram of the initial heating and cracking portion of the system showing a modified arrangement in which the preheater of Fig. 2 is placed in tandem with the ordinary

- preheater, flashpot, and cracking still, also showing the vacuum pump on the outlet of the cracking still, which in this case functions as a super-cracker.
- 5 Referring to the drawings and first to Fig. 1, the principal pieces of apparatus employed in this system are the preheater 51, the flashpot 1, the cracking still 56, the dephlegmators or fractionators 6, 7, 8, and the suction pump 14 connected 10 between the cracking coil 56 and the dephlegmator tower 6. Much of the detail in these drawings will not be claimed herein, as it forms the subject matter of claims in prior copending applications, but the complete system will be 15 briefly described and its operation stated, in order to furnish a proper and complete foundation for the claims herein, which will be directed to the combination of the essential features above stated, with particular reference to the location 20 of the pump 14 between the cracking still and the dephlegmators or fractionators, so as to maintain a sub-atmospheric pressure on the cracking still and the flashpot, and an atmospheric or super-atmospheric pressure on the rest 25 of the system extending forwardly from pump 14 to the coil 9 and the separator 10 and backwardly from pump 15 for reflux fractions through heat exchangers 28-27-26 and the pipe 22 to the flashpot.
- 30 Each of the pumps 12, 13, 14, 15, 16 is supposed to be driven by a suitable source of power. Each of the dephlegmators may be of the bubble tower type as shown at 7-8, or of the baffle plate type as shown in 6. From the top of each 35 tower a goose neck extends down to below the middle of the next succeeding tower and from the top of the last tower 8 to the cooler or condenser 9 and separator 10. From the latter a valved pipe 29 carries off the condensate and the pipe 30 draws off uncondensed gases. Each of the 40 towers contains in its top a heat exchanger 23, 27, or 28, whose area and capacity is increased in the direction of flow, to provide for the rising temperature of the reflux oils. The inlet of the 45 first of these heat exchangers 23 is connected through the valved pipe 32 to the outlet of the pump 15, with valved branch 31 to the top of the absorbing tower 11, and to a source of supply of make-up oil, the flow from which is regulated 50 by valve 35. From the outlet end of the heat exchanger 26, the pipe 22 extends to the flashpot 1 direct, without going to the preheater 51. Charging stock is fed into the preheater under 55 pressure by the pump 54 and in order to build up pressure and accumulate thermal units in the coil 57, the valve 23 is provided which in operation is complementary to the valves 35 and 38. Means are provided to regulate the heating of the reflux fractions in the heat exchangers 27, 28. These 60 are shown in the drawings as by-passes controlled by valves 36, 37, which like the other valves described can be set at anything from closed to open.
- 65 The function of the pump 12 is to draw off the heavy precipitate or tarry matters from the bottom of tower 6; the function of pump 13 is to draw off heavy gas oil which is thrown down in the bottom of tower 7 and return the same in part through valve 18 to the middle section of tower 6 70 and in part through valve 47 to the heat exchanger 26 as reflux to be retreated. The function of pump 14 is to produce suction through the valve 4 on the outlet of the cracking still 56, and conversely to build up ahead of it through pipe 75 39 and valve 5 a constant positive pressure, that
- is to say, a pressure at or above atmospheric, in the towers 6-7. The function of the pump 15 is to withdraw light gas oil from the bottom of tower 8, drawing it through the heat exchanger 17 and discharging it either in whole or in part through the valved branch 31 into the upper part of absorption tower 11, or in whole or in part through the valved branch 32, into the heat exchangers 28-27-26. The portion discharged through the valve 31 into the tower 11 has for 10 its function the absorption of gasoline-like fractions which have become entrained with the fixed gases. These gases flow through the pipe 30 under their own pressure and are discharged through the valve 25 and the pipe 42 into the lower part of 15 the tower 11. The entrained gasoline-like material is stripped from them and absorbed by the oil entering the head of the tower through the valve 31. This tower as well as the towers 7-8 20 is shown as a bubble tower, but it is to be understood that any preferred form of tower may be employed which will afford a larger superficial area over which gases passing in one direction and the oil passing in the other may come into contact.
- 25 The pipe shown leading from the pump 15 vertically to the valves 31-32 is also provided with a horizontal branch 34 through which make-up oil is supplied to the system. This make-up oil as its name indicates, is to supply in part or in 30 whole, the losses due to conversion, condensation, and removal from the system through the cooler 9 and the separator 10, or otherwise. Since this make-up oil may be in part used through the valve 31 as an absorbing agent in the tower 11, 35 for which purpose light gas oil is also drawn by pump 15 through the heat exchanger 17 from the bottom of tower 8, obviously the make-up oil to cover this purpose may be gas oil.
- 37 The operation of the system thus described is 40 as follows: charging stock is pumped into the primary heater 51 by pump 54 and is heated in the furnace 2a to a temperature higher than that required for vaporization at the pressure maintained in the flashpot, or in other words, the 45 charging oil is heated under pressure. It is then admitted through valve 23 to the flashpot wherein it instantly passes in the vapor phase. In this form it is drawn in a turbulent, rapidly moving body through the cracking coil 56 into and 50 through the pump 14 and so into the tower 6 through the valved pipe 5. In this tower the first separation takes place, the vapors as they rise meeting the gas oil entering the tower through valve 18 and also encountering the surfaces of 55 the heat exchanger 26. The result is a deposit of heavy fractions or a tarry mixture which is removed from the system by the pump 12. The heavy gas oil admitted through the valve 18 dilutes this tarry mixture so as to prevent the 60 deposit of any dried coke or the burning on of coke or tar in the tower.
- 65 The vapors thus initially cleansed pass over the first goose neck into the lower part of the second tower 7 and rise up through the bubble pans and 65 through the reticulations of the heat exchanger 27. There is thrown down in this tower (assuming the crude to be of average formula) heavy gas oil, which is drawn off by the pump 13 and carried back to the tower 6 as above stated. The 70 vapors, having given up more heat through the heat exchanger 27, pass through the second goose neck to the lower part of the third tower 8 through which they bubble up as before and in addition to the bubble pans, they pass through the reticu- 75

lations of the heat exchanger 28. The condensate in this case is a light gas oil, and the vapors remaining go over through the top of the tower and the third goose neck to the cooler 9 wherein 5 condensable portions are condensed and pass to the separator 10. Valved pipe 29 leads from this separator 10 to storage, while the pipe 30 goes to the tower 11, carrying fixed gases with entrained gasoline-like material. These gases flow back 10 under their own pressure through valve 25 into pipe 42 to the lower part of tower 11, as indicated by the arrows. In this tower as already stated make-up oil and/or light gas oil drawn from the bottom of tower 8 through heat exchanger 17 are 15 or is fed into the upper part of the tower 11 through the valve 31 and meeting the uprising fixed gases, absorbs the gasoline carried thereby and carries the same down with it to the bottom of the tower 11 from whence it is drawn off by 20 pump 16 and forced back through the heat exchanger 17 and the valve 33 into the tower 8. Becoming heated and vaporized in this path, the gasoline rises, goes over the top to the goose neck, and is condensed in the cooler 9 and passes 25 through the separator 10 to the storage tank. The fixed gases in tower 11 pass out of the top thereof through the waste pipe 48.

It is obvious that it is possible to adjust the valve 35 and the valve 32 or the valves of the 30 pump 54 typified at 540 so that the charging stock and the make-up oil will be fed in in complementary quantities and so as to maintain complementary or average temperatures and pressures in the pipes 22 and 52 leading to the flashpot. The 35 valves 23 and 38 materially assist in this adjustment, so as to produce uniform average temperature and pressure at the flashpot, whether the input is fresh charging stock, or whether it is make-up oil or reflux fractions drawn from the 40 tower 8 by pump 15, or make-up oil entering the system through pipe 34.

Referring now to Figs. 2 and 3, I have therein shown a modification of the preheating apparatus and the cracking apparatus of the type described and illustrated in my prior application, Serial No. 442,871. In Fig. 2, the preheater 57 and the cracking coil 56 are installed the same as before, but between these two in respect to the flow of oil, and taking the place of the flashpot, 45 I provide a cracking tube 110 constructed as described in U. S. Letters Patent 1,723,805, granted October 22, 1929 to E. C. D'Yarmett. In Fig. 3, the same type of cracking tube 110 is inserted between the flashpot 1 and the cracking coil 56. 50 In either case, the tube 110 contains a set of vertical paddles or blades projecting radially in the tube from a central shaft coaxial therewith, which shaft carrying the paddles is rotated by a motor 116 at such speed that the oil, is spread 55 around the inside surface of the tube as a film by centrifugal force. The shaft is journalled at top and bottom of the tube 110 as indicated at 110a and 110b. In the form illustrated in Fig. 2, charging oil after leaving the pump passes 60 through the coil 57 and pipe 52 to the bottom end of the tube 110, into which it is expanded by manipulation of the valve 38a. Reflux oil and make-up oil coming through the heat exchangers 26, 27, 28 and the pipe 22 follows the same path 65 through the valve 38a to the lower end of the tube 110 and is flashed therein into vapors. Sufficient temperature is maintained in the furnace 101 to produce cracking in the film of oil around the inside of the tube 110, and the partially

cracked vapors then pass through the outlet pipe 55 to the still 56 which in this case performs the function of a supercracker. The pump 14 maintains sub-atmospheric pressure on this cracking still 56 and therethrough and through the pipe 55 also on the tube 110, which performs the functions of the flashpot in Fig. 1 in addition to assisting in cracking the vapors.

In Fig. 3, the flashpot 1 is retained, and the heated charging stock pumped in from 54 through the pipe 53 and the preheater 57, reaches the flashpot 1 through the pipe 52 as in Fig. 1. Heated reflux fractions and make-up oil are also brought over through the pipe 22 to the flashpot 1 as Fig. 1. From the flashpot, instead of carrying the outlet direct to the cracking coil 56, the discharge pipe 121 is carried to the lower end of the tube 110, from the top of which pipe 55 goes to the cracking coil 56. The tube 110 is set in the furnace 101 and its internal paddles are rotated 20 by the motor 116 so as to maintain a film of oil vapors around the inside of the tube. Heat conducted through the walls of the tube acts very efficiently upon this film which is constantly changing and very turbulent, owing to the vacuum or subatmospheric pressure produced by the pump 14 shown at the right of the figure. In this case the coil 56 acts as a super-cracker, since part of the cracking in the vapor phase and under subatmospheric pressure takes place in the tube 30 110. The action of the pump 14 is the same in each case however, viz., to create and maintain a partial vacuum or subatmospheric pressure from its inlet back to the point where the vapors are flashed, and to create and maintain a positive pressure from its outlet side through the fractionators. It may be noted that all deposits from the flashpot and in the pipe 121, and the tube 110 may be drained off through the pipe 240 which is valved at 24. 40

What we claim is:

1. Apparatus for the treatment of hydrocarbon oils comprising in combination an initial heater adapted to retain pressure, a feed pump connected to the inlet of said heater and adapted to positively produce pressure therein sufficient to store up heat energy by substantially raising the boiling points of the oils, an expansion chamber or flashpot, a connecting pipe extending from the outlet of said initial heater to said flashpot and 45 a valve in said pipe adapted to release the initially heated oils from said heater into said expansion chamber or flashpot, a still having an open connection to said flashpot adapted to receive the oil vapors therefrom, and means to heat 50 the oils to cracking temperature in the vapor phase in said still, cooling and separating means connected through a suitable pipe line to the outlet of said cracking still to receive the cracked vapors therefrom, and a pump connected in said 55 pipe line and adapted to positively create and maintain a constant vacuum or subatmospheric pressure on the oil vapors in said cracking still and through its open connection with the flashpot on the content of said flashpot. 60

2. The combination described in claim 1, in which the pump connected in the pipe line between the cracking still and the cooling and separating means is adapted to positively create and to maintain a positive pressure above atmospheric 70 on the cracked vapors in said cooling and separating means.
